UNITED STATES PATENT OFFICE.

FRANCES M. CONSTABLE, OF COLUMBUS, OHIO.

CURTAIN-STRETCHER.

1,365,584.

Specification of Letters Patent. Patented Jan. 11, 1921.

Application filed April 19, 1920. Serial No. 374,786.

To all whom it may concern:

Be it known that FRANCES M. CONSTABLE, a citizen of the United States, residing at Columbus, in the county of Franklin and 5 State of Ohio, has invented certain new and useful Improvements in Curtain-Stretchers, of which the following is a specification.

This invention relates to curtain stretchers, and has for its primary object to provide 10 a curtain stretcher of novel, simple and improved construction, and which is of such form that the same may be readily connected with a window frame or other equivalent structure for the purpose of 15 stretching curtains while the same are applied to the frame.

In carrying out the invention, I preferably employ a plurality of brackets which are of such construction that the same may 20 be detachably clamped to the sill of a window frame and to provide a vertically adjustable stretcher bar in connection with said brackets with which the lower edges of a curtain may be detachably connected, 25 whereby upon the vertical adjustment of the bar with respect to said brackets, the necessary tension may be imparted to the curtain to effect the desired stretching of the latter.

Another object of the invention resides in 30 a curtain stretcher which is of simple and economical formation, may be readily applied in its operative position and when not in use will be of such proportion and 35 construction as to occupy but a minimum of storage space.

With these and other objects in view, as will appear as the description proceeds, the invention accordingly consists in the novel 40 features of construction, combinations of elements and arrangement of parts, herein- 45 after to be fully described and to have the scope thereof pointed out in the appended claims.

In the accompanying drawing, forming a 50 part of this specification and in which similar characters of reference denote like and corresponding parts throughout the several views thereof:

Figure 1 is a side elevation of the improved curtain stretcher comprising the present invention and illustrating the application of the latter to a window frame.

Fig. 2 is a detail perspective view of one 55 of the curtain stretcher brackets, and,

Fig. 3 is a detail vertical transverse section view taken through the stretcher.

The curtain stretcher 1 comprising the present invention consists essentially of a horizontally disposed stretching bar 2. This bar is of the usual formation provided in curtain stretcher constructions, and is preferably formed from wood, the same embodying the usual longitudinally disposed pins 3 with which the lower edge of a curtain 4 is adapted to be detachably connected. This bar 2 is arranged to be adjustably carried by a pair of metallic brackets 5. These brackets are of angular formation and are so constructed as to embody vertically disposed legs 6, angularly disposed terminating ends 7 and sill engaging ledges 8. The legs 6, as shown, are provided with elongated vertically disposed slots 9 which are of such width as to receive the horizontally disposed shanks of clamping bolts 10. The heads of these bolts are arranged on the inner sides of the legs 6, and the shanks thereof are so disposed as to extend through the slots 9 and also through elongated horizontally disposed slots 11 provided in the ends of the bar 2. Threaded ends of the bolts 10 are arranged to receive wing nuts or their equivalents 12, which are adapted to be threaded into engagement with wear receiving washers 13 which are so disposed as to protect the material of the bar from being damaged by the pressure exercised when said nuts occupy their clamping positions. The ends 7 of the brackets are also provided with threaded openings which are arranged to receive vertically disposed clamping screws 14, the latter being moved relatively toward or away from the ledges 8 and are provided with felt covered ends 15.

In operation, the stretcher is set up in its applied position by locating the brackets 5 at the opposite ends of a window sill 16, said sill being received between the upper ends 7 of said brackets and the ledges 8. The brackets are then firmly yet detachably clamped to the sill by rotating the screws 14. This results in causing said screws to frictionally engage with the upper surface of the sill with ample and sufficient pressure to maintain the brackets in their applied positions. By protecting the ends 15 of the screws, it will be obvious that the window frame construction will not be damaged by the engagement of the screws therewith.

The upper edges of the curtain 4 may be connected with the window frame 17 in any suitable manner, such for example by means of rods 18, normally found to effect the support of the curtain, while the lower edge of the latter is connected to the bar 2 by means of the pins 3. It will be noted that the stretcher as a whole may be adapted readily to the width of a curtain, and this is effected by shifting the longitudinal positions of the brackets 5 upon the sill 16, the horizontal slots 11 in the ends of the bar 2 serving to adapt the latter to this horizontal adjustment. The desired tension may be then placed upon the curtain 4 by lowering or raising the bar 2 relatively to the brackets 5. This allows the bolts 10 to loosely slide within the slots 9, and when the desired adjustment is reached, the same may be maintained by threading the wing nuts 12 inwardly upon the threaded ends of the bolts 10. This results in frictionally clamping the bar 2 in a rigid manner with the brackets 5 and thus prevents undue movement on the part of said bar.

From the foregoing description, taken in conjunction with the accompanying drawing, it will be apparent that there is provided a curtain stretcher of very simple yet efficient construction and one of considerable utility in its particular field. The very simplicity of the stretcher enables the latter to be quickly set up for use and by being attachable to a window frame, the same will

enable its user to stretch accompanying curtains to such lengths as will be necessary to adapt the curtains to the proportions of the window frame. When not in use, the stretcher will occupy but a minimum of storage space and furthermore said stretcher 40 may be admirably used in restricted areas.

What is claimed is:

1. A curtain stretcher for window frames comprising a pair of angular brackets, threaded means for detachably securing 45 said brackets at various longitudinal positions upon the sill of a window frame, a stretcher to which the edges of a curtain may be secured, and clamping screws connecting said bar with said brackets for vertical and horizontal adjustments with regard thereto.

2. A curtain stretcher for window frames, comprising a pair of spaced brackets, said brackets being formed to include vertically 55 slotted legs, the upper ends of said legs being angularly bent, a clamping screw threadedly carried by said ends, a sill engaging ledge stationarily carried by said brackets and toward which said screws are 60 relatively movable, a stretcher bar horizontally connecting said brackets, and clamping screws passing through said bar and through the vertical slots of said legs to permit of vertical adjustment on the part of said bar. 65

In testimony whereof I affix my signature.

FRANCES M. CONSTABLE.
